US00D910290S

(12) **United States Design Patent** (10) **Patent No.:** **US D910,290 S**
Girard et al. (45) **Date of Patent:** **** Feb. 16, 2021**

(54) **SHOE**

(71) Applicant: **PUMA SE**, Herzogenaurach (DE)

(72) Inventors: **Romain Girard**, Lauf an der Pegnitz (DE); **Matthias Hartmann**, Forchheim (DE)

(73) Assignee: **Puma SE**, Herzogenaurach (DE)

(***) Term: **15 Years**

(21) Appl. No.: **29/743,089**

(22) Filed: **Jul. 17, 2020**

Related U.S. Application Data

(60) Continuation-in-part of application No. 29/715,969, filed on Dec. 5, 2019, now Pat. No. Des. 907,344, (Continued)

(57) **CLAIM**

The ornamental design for a shoe, as shown and described.

DESCRIPTION

FIG. 1 is a left side perspective view of an ornamental design for a shoe;

FIG. 2 is a left side view of the shoe of FIG. 1;

FIG. 3 is another left side view of the ornamental design with alternative environmental structure; and,

FIG. 4 is yet another left side view of the ornamental design with alternative environmental structure.

The dash-dash-dash broken lines are included for the purpose of illustrating portions of the shoe that form no part of the claimed design.

1 Claim, 4 Drawing Sheets

Related U.S. Application Data

which is a continuation of application No. 29/682, 372, filed on Mar. 5, 2019, now Pat. No. Des. 885, 724, which is a division of application No. 29/621, 562, filed on Oct. 10, 2017, now Pat. No. Des. 855,953.
